UNITED STATES PATENT OFFICE.

WILLIAM L. LIGGINS, OF ST. LOUIS, MISSOURI.

ALCOHOL-LAMP.

1,228,328.

Specification of Letters Patent.

Patented May 29, 1917.

Application filed January 25, 1916. Serial No. 74,174.

To all whom it may concern:

Be it known that I, WILLIAM L. LIGGINS, a citizen of the United States, residing at St. Louis, in the State of Missouri, have invented certain new and useful Improvements in Alcohol-Lamps; and I do hereby declare the following to be a full, clear, and exact description of the invention, such as will enable others skilled in the art to 10 which it appertains to make and use the same.

This invention relates to new and useful improvements in alcohol lamps and one of its objects is the provision of a device of 15 this character, which shall be simple, durable and efficient and which may be manufactured and sold at a comparatively low cost.

A further object of this invention is the 20 provision of means for supporting soldering irons, hair curling irons, etc., in a horizontal position so that the ends of the devices will extend into the flame to be heated.

With these and other objects in view as 25 will become more apparent as the description proceeds, the invention consists in certain novel features of construction, combination and arrangement of parts as will be hereinafter more fully described and 30 claimed.

For a complete understanding of my invention, reference is to be had to the following description and accompanying drawings, in which:—

35 Figure 1 is a side elevation of an alcohol lamp, constructed in accordance with my invention, and

Fig. 2 is a top plan view of the device, 40 illustrating the supporting arm in a folded position.

Referring in detail to the drawings, 1 indicates a body of the lamp, having a plurality of legs 2 secured thereto and having their ends bent at right angles to provide 45 feet 3 for supporting the body 1 of the lamp. The body 1 is provided with a circular opening in the top thereof and has a flange 4 extending around the opening which is internally screw-threaded to receive 50 a lamp burner 5 of any well known type in which a wick tube 6 receives a wick 7 and wick operating means 8. The burner may be readily detached and attached within the opening so that the body 1 may be 55 filled with alcohol when desired.

A pair of supporting arms 12 and 13 are

hinged as illustrated at 14 to the top of the body 1 and are provided with their free ends curved as at 15 to support various types of tools in a horizontal position so that their ends may be heated within the flame from the wick 7. The lower ends of the arms 12 and 13 are bent at right angles to form supporting feet when the arms are disposed in a vertical position for supporting tools. The lower ends of the arms form right angled bases which rest upon the top of the body to support the arms in an upright position with relation to the body for supporting curling irons or like devices 60 directly over the burner, the bases having barrels formed on their sides to receive pintles which are secured to the top of the body in relatively spaced relation for permitting the arms to be folded in parallel relation 65 to the top of the body and in slightly spaced relation therefrom to form handles for carrying the body from one point to another. The arms are each flared laterally in the direction of the free ends to provide heads 70 adapted to prevent the grasp from slipping from the hands, when desiring to use either of the arms as handles when in upright position. When using the arms as handles, when in upright position, the bases rest 75 upon the top of the body, preventing the body from tipping in relation to the hand or handles.

While I have shown and described the preferred embodiment of my invention, it 80 will be understood that minor changes in construction, combination and arrangement of parts may be made without departing from the spirit of the invention as claimed.

Having thus described my invention, 85 what I claim is:—

An alcohol lamp comprising a body, a burner located near one end of the body, and a pair of sheet metal arms, one end of each arm being bent to provide a right angled base having a hinged barrel on one side thereof, pintles passing through said barrels and secured in relatively spaced relation to the upper side of said body to permit said arms to be folded one upon the 100 other in parallel relation to said top and to be supported by said bases in an upright position with relation to said top, the bases fully engaging said top below said pintles and each arm being located to one side of 105 its pintle when the arms are in upright position so as to prevent the arms from acci-

dentially falling into folded position, either of said arms when in upright position forming a handle, by which the lamp may be moved from place to place, and the side edges of said arms being flared laterally in the direction of the free ends to provide heads adapted to prevent the grasp from slipping through the hands, the upper edges of said arms being recessed to receive a 10 curling iron, and said bases supporting the

arms when folded above said top so as to permit the folded arms to be used as a handle also.

In testimony whereof I affix my signature in presence of two witnesses.

WILLIAM L. LIGGINS.
